ATTORNEY

UNITED STATES PATENT OFFICE.

CHARLES E. TUNELIUS, OF CHICAGO, ILLINOIS.

ROTARY FAN.

SPECIFICATION forming part of Letters Patent No. 293,286, dated February 12, 1884.

Application filed July 16, 1883. (No model.)

To all whom it may concern:

Be it known that I, CHARLES E. TUNELIUS, of Chicago, in the county of Cook and State of Illinois, have invented certain new and useful Improvements in Rotary Fans; and I do hereby declare that the following is a full, clear, and exact description of the invention, which will enable others skilled in the art to which it appertains to make and use the same, reference being had to the accompanying drawings, and to letters of reference marked thereon, which form a part of this specification.

The object of my invention is to provide a rotary fan, for exhaust and ventilation purposes, the vanes of which, when they become injured or useless, can be replaced without necessitating the opening of the case and the removal and abandonment of the entire rotary fan. This I accomplish by making each vane removable from a hub or boss made of two or more parts, and provided with means for receiving and locking therein the shank of said vanes, as will be hereinafter more fully described, and as illustrated in the drawings, in which—

Figure 1 is a vertical longitudinal section of my improved fan. Fig. 2 is a front view of the same. Fig. 3 is a perspective view with the washer and nut removed, and Fig. 4 is a perspective view of one of the vanes.

In the drawings, A represents a vane having an angle-iron rib, a, on either side, which unite, after leaving the base of said vane, to form a T-iron shank, B. Near the extremity 35 of this shank, in that part of the T-iron which is at right angles to the other two arms, is a transverse mortise, b, forming a cog, c, on the extremity of said shank.

The end of the shaft C on which the boss 40 of my rotary fan is placed is preferably stepped, and the extremity of the stepped portion is screw-threaded.

The boss of the rotary fan is composed of two sections, D and E, and their contiguous faces are brought nearly together by means 45 of a nut, F, on the screw-threaded extremity of the stepped part of the shaft. In the inner face of the section E of the said boss is a series of mortises corresponding to the number

of vanes, and corresponding to the shape of 50 the extremity of the T-iron shank B. Thus there is a broad shallow mortise, d, corresponding in depth and width to the horizontal T-iron shank B, and a central mortise, d', designed to receive the mortised extremity of 55 the said T-iron, and therefore being made deeper immediately next the annular bearing-surface of the said boss to receive the cog c. These mortises divide the face of the said section E into a number of equal spaces. It 60 will therefore be readily perceived that if these mortises intersect each other near their radial centers, the contiguous end edges of the horizontal arms of the T-iron will be correspondingly beveled, to permit their easy ad- 65 justment in position.

When the vanes are all in position, section E—which is, in fact, a washer—is brought to bear against the contiguous surfaces of the T-iron shanks, to hold them securely in position, 70 and is held in such position by means of a nut, F, on the end of the shaft, or by bolts passing through the same and into the section E, as shown in dotted lines in Fig. 2.

If it is desired to have a vane with two arms, 75 which is usual when the fan is very broad, the mortises are made in section E, of which there are two, with a sleeve placed between them, the boss being held together similar to the single-arm vane.

I do not confine myself to the particular construction of that part of the shank B within the boss, or the general design of the mortises for receiving the same, as it is obvious many immaterial changes could be made in that respect without departing from the spirit of my invention, which is, in substance, the rotary fan having a sectional boss, with means for receiving and holding in position the removable vanes, substantially as hereinbefore described. 85 90

What I claim as new is—

1. A rotary fan for exhaust and blowing purposes, consisting of removable vanes provided with suitable shanks, and a sectional boss having a suitable formation corresponding to the extremity of said shanks, said vanes being removable by the separation of the sections of said boss. 95

2. The combination, with the vane having angle-iron ribs and a T-iron shank, recessed in the manner hereinbefore set forth, of a boss composed of two sections, one of which is 5 mortised to receive the T-iron of said shank, and the other of which is a washer bearing against and confining said shank in position, the whole kept together by means of bolts or nuts.

In testimony that I claim the foregoing as 10 my own I hereunto affix my signature in presence of two witnesses.

CHARLES E. TUNELIUS.
